[57] CLAIM

The ornamental design for a basketball cup, as shown and described.

DESCRIPTION

FIG. 1 is a top plan view of a basketball cup showing our new design;

FIG. 2 is a side elevational view thereof in which both left and right sides are identical,

FIG. 3 is a front elevational view thereof,

FIG. 4 is a bottom plan view thereof,

FIG. 5 is a top plan view of a basketball cup showing a second embodiment of our new design;

FIG. 6 is a side elevational view of the second embodiment

in which both left and right sides are identical,

FIG. 7 is a front elevational view of the second embodiment; and,

FIG. 8 is a bottom plan view of the second embodiment.
